**CONTROL APPARATUS AND CONTROL DEVICES
FOR USE THEREIN****Adolph J. Hilgert, Milwaukee, Wis., assignor to Baso Inc.,
a corporation of Wisconsin.****Filed Aug. 6, 1956, Ser. No. 602,390****2 Claims. (Cl. 200—83)**

The present invention relates to control apparatus and control devices for use therein, but more particularly to apparatus wherein a condition sensitive control device responds to a given condition but only when said condition is provided in a predetermined manner or by predetermined means.

Certain fluid fuel burning apparatus, particularly those wherein the heating unit is placed considerable distance from the chimney or stack, utilize fans or blowers of one type or another for moving exhaust gases and other products of combustion from the bonnet or plenum chamber and transmitting the same to the chimney or stack for flow to the atmosphere. Such fan or blower is particularly necessary in fluid fuel burning apparatus wherein the heating unit is relatively large with respect to the air ducts which bring in secondary air for satisfactory burning of the fuel emitted by the main burner and which afford removal of the products of combustion to the atmosphere. Without such fan or blower, the air within the combustion chamber might not be changed frequently enough to afford adequate combustion of the main burner fuel (depending on the size of the heating unit with respect to the size of the air ducts), thereby causing exhaust gases and other products of combustion to accumulate within the combustion chamber and extinguish the main burner flame and/or prevent satisfactory ignition thereof. Such extinguishment of the flame at the main burner might not be accomplished by extinguishment of the pilot burner flame, wherefore unburned fuel is emitted from the main burner into the enclosure of the heating unit. As is readily understandable, such a condition is extremely dangerous. In order to prevent occurrence of such a hazardous condition, fan or blower means is provided to afford a constant supply of secondary air to the main burner. However, since such fan or blower means is subject to malfunction and faulty operation, control means capable of distinguishing between satisfactory and faulty operation of the fan must be employed. In this regard, pressure sensitive control devices have been utilized to sense the pressure variation within the bonnet as caused by satisfactory operation of the fan means.

Such pressure sensitive devices heretofore in use have usually employed electrical contacts in the energizing circuit of a solenoid valve, which, as is understood in the art, requires 24 or 110 volts for satisfactory operation. Because of the use of such relatively large electrical power, the electrical contacts of pressure sensitive devices heretofore used could be exposed to the surrounding atmosphere or to the exhaust gases and other products of combustion without interfering appreciably with the life of the control device. However, the use of outside power, whether on the order of 24 or 110 volts, is undesirable since it precludes the advantages inherent in self-powered units which operate on a minimal amount of electrical power (on the order of 25 mv.). Electrical contacts for use in a low power circuit must be of exceptionally low resistance, and hence cannot be exposed to foreign matter

2

which may have a deleterious effect on the life and operation of such contacts. Thus such electrical contacts must be protected by enclosure means which does not disturb the sensitivity of the pressure responsive device to changes in pressure caused by satisfactory operation of the exhaust fan.

It is therefore an object of the present invention to provide a pressure sensitive control device for use in low power circuits and which is capable of distinguishing between pressure variations provided by means employed for that purpose and pressure variations caused by changes in atmospheric pressure.

Another object is to provide for use in low power circuits a pressure sensitive control device having cooperating control members enclosed within an hermetically sealed enclosure to prevent accumulation thereon of foreign matter, said control members being relatively movable between controlling positions upon a predetermined variation in pressure but only when such variation is caused in a predetermined manner.

Another object is to provide, for use in a thermoelectric circuit, a pressure sensitive control device which is extremely sensitive to pressure variations produced by means provided for that purpose.

Another object of this invention is to provide a pressure sensitive circuit controlling device having hermetically sealed low resistance electrical contacts for use in a thermo-electric circuit, there being means permitting response of said device to pressure variations caused in a predetermined manner only.

Another object is to provide heating apparatus having a pressure sensitive circuit controlling device, as characterized above, in circuit with a thermoelectric generator and fuel flow control means for said heating apparatus, said circuit controlling device being responsive to pressure variations within the bonnet of the heating unit when caused by satisfactory operation of a fan or blower in moving the products of combustion from within the bonnet to thereby permit energization of the fuel flow control means for supplying fuel to the main burner of the heating apparatus.

Another object is to provide heating apparatus in accordance with the preceding paragraph and wherein said pressure sensitive device comprises hermetically sealed low resistance contacts for control of the thermoelectric current afforded by said thermoelectric generator.

Another object is to provide a pressure sensitive control device of the diaphragm type including a stationary contact, a movable contact fixed to the diaphragm, and hermetic enclosing means for protection of said contacts, said enclosing means comprising a stationary portion and a portion fixed relative to one side of said diaphragm, there being means fixed relative to the other side of said diaphragm to compensate for the loss in effective area of the side of the diaphragm to which said enclosure is fixed, whereby the area of the opposite sides of said diaphragm are maintained substantially equal so as to effect cancellation of atmospheric pressure variations exposed to both sides.

The novel features which I consider characteristic of my invention are set forth with particularity in the appended claims. The device itself, however, both as to its organization and mode of operation, together with additional objects and advantages thereof, will best be understood from the following description of specific embodiments when read in connection with the accompanying drawing, in which the subject pressure sensitive control device is shown in section and connected, more or less schematically, in circuit with fuel flow control means for a forced air heating unit.

Referring to the drawing, it shows a heating unit 10

comprising a sheet metal shell or enclosure 12 providing a combustion chamber 14 and a bonnet or plenum chamber 16. An air inlet duct 18 is afforded communication with combustion chamber 14 and an air outlet duct 20 is afforded communication with plenum chamber 16. A fan or blower 22 (not shown in detail) is operatively connected to outlet duct 20 for drawing products of combustion out of chambers 14 and 16 for expulsion to the atmosphere through a chimney or stack (not shown) as will hereinafter become apparent.

Positioned within enclosure 12 is a heat exchanger 23, there being an air inlet duct 25 and an air outlet duct 27 in communication therewith and extending through respective openings in enclosure 12. Air ducts 25 and 27 are part of heat transmitting means for transmitting heated air from exchanger 23 through duct 27 to a space to be heated, and for bringing air to be heated into exchanger 23 through duct 25.

Positioned within an opening in the side wall of chamber 14, is a fluid conduit 24 having one end connected to a source of fluid fuel (not shown) and another end connected to a fluid flow control device 26. One end of a fluid conduit 28 is connected to control device 26 while the other end thereof is connected to a main fuel burner 30. Flow control device 26 comprises a flow control member or valve 32 having flow-permitting and flow-preventing cooperation with a valve seat 34. Control device 26 is also provided with an electromagnetic operator 36 having an electromagnet winding 37 energizable to effect movement of valve member 32 from its flow-preventing to its flow-permitting position by means of an operating lever 38 pivotally mounted at 40. A return spring 42 is provided for return of valve member 32 to its flow-preventing position in engagement with valve seat 34 upon deenergization of electromagnet winding 37. A pilot or ignition burner 44 is positioned adjacent main burner 30 for ignition thereof as is well known in the art, a pilot fuel supply conduit 46 affording communication between pilot burner 44 and conduit 24.

Fixed to bonnet 16 within an opening formed therein, is a fluid conduit 48 for transmission of fluid pressure from bonnet 16 to a condition sensitive control device 50. Control device 50 comprises an enclosure 52 formed of oppositely disposed cup-shaped members 54 and 56 having substantially identical interior dimensions. Conduit 48 is afforded communication with the interior of cup-shaped member 54 through an opening 54a formed in the latter, there being a compression fitting comprising an externally threaded member 58 welded to or formed integrally with cup-shaped member 54, a nut 60 formed with internal threads for cooperation with member 58 and a gas tight sealing member 62 for gripping an enlarged end portion 48a of conduit 48 when nut 60 is firmly threaded onto member 58.

Interposed between cup-shaped members 54 and 56 is a pressure sensitive actuating means in the form of a flexible diaphragm 64. Each of the members 54 and 56 is formed with an annular flange 54b and 56b respectively, there being aligned openings for receipt of rivets 66 for fastening said members 54 and 56 in their oppositely disposed positions with diaphragm 64 therebetween to provide separate pressure cavities or chambers 54c and 56c respectively. Positioned adjacent diaphragm 64 within cavity 54c, is a diaphragm reenforcing member 68. Attached to member 68 as by welding or the like, is a movable mounting member 70 carrying a movable control member in the form of an electrical contact 72 formed integrally therewith or attached thereto in any well known manner. A stationary mounting member 74 is secured to cup-shaped member 54 within cavity 54c and is formed with an opening 74a aligned with an opening 54d formed in member 54. I prefer to employ insulating glass seal mounting means 76 for retaining an elongated stationary control member in the form of an

electrical contact member 78 in fixed position relative to mounting member 74. Mounting means 76 comprises a tubular brass member 80 positioned within opening 74a and formed with an annular shoulder 80a in engagement with mounting member 74 as shown in the drawing. Interposed between member 80 and stationary contact member 78 is an insulating member 82 formed of glass or ceramic material.

Member 54 is formed with a female connector portion 84 about opening 54d for receipt of a male connector as is well known in the art. Positioned within opening 54d of member 54 and about the intermediate portion of contact member 78 is an insulating member 86, said contact member 78 being formed with enlarged end portion 78a in engagement with member 86. Stationary contact member 78 is formed with a hemispherical electrical contact 88 for cooperation with movable contact 72 as will hereinafter appear.

An electrically conductive expandable and contractible bellows 90 having one end fixed to movable mounting member 70 and the other end fixed to stationary mounting member 74 affords an hermetic enclosure for contacts 72 and 88. I prefer to utilize a subatmospheric fill of inert gas for enclosure or bellows 90 to minimize chemical decomposition of contacts 72 and 88 and to insure separation of said contacts in the event of rupture of bellows 90.

Fixed to diaphragm 64 within cavity 56c is an hermetic enclosure 92 formed substantially identically with the enclosure for contacts 72 and 88. Enclosure 92 comprises a movable mounting member 94 formed substantially identically with mounting member 70 and an adjustable stationary end wall 96. An expandable and contractible enclosure or bellows 98 formed substantially identically with bellows 90 has one end fixed relative to movable mounting member 94 and one end fixed relative to stationary end wall 96. Formed integrally with stationary end wall 96 is a stud 100 formed with external threads and extending through an opening 56d formed in the side wall of cup-shaped member 56. Stud 100 is formed with a screw driver kerf or slot 100a and is adapted with a nut 102 for adjusting the position of stationary end wall 96 for a purpose to be hereinafter explained.

Cup-shaped member 56 is formed with an opening 56e for exposing cavity 56c to atmospheric conditions.

Positioned adjacent pilot burner 44 to be heated by a flame thereof, is a thermoelectric generator or thermocouple 104. An electrical conductor 106 affords connection between one of the cold junctions of thermocouple 104 and the enlarged end portion 78a of stationary contact member 78. An electrical conductor 108 affords connection between the other cold junction of thermocouple 104 and one end of winding 37 of electromagnetic operator 36. The other end of winding 37 is grounded as at 110 while cup-shaped member 54 is grounded as at 112 to provide an electrical circuit from one side of thermocouple 104 through conductor 108, winding 37, grounds 110 and 112, cup-shaped member 54, mounting member 74, bellows 90, mounting member 70, contacts 72 and 88 and electrical conductor 106 to the other side of thermocouple 104.

The operation of the subject apparatus will now be described.

The first step in placing the apparatus in operation, following ignition of pilot burner 44, is to energize fan 22. Operation of fan 22 decreases the fluid pressure within plenum chamber 16 thereby causing the air therewithin to be drawn through air outlet duct 20 and forced to the chimney or stack for expulsion to the atmosphere. Such movement of air causes air to be drawn into combustion chamber 16 through air inlet duct 18, this process being continuous as long as fan 22 continues to operate satisfactorily. The decrease in fluid pressure within plenum chamber 16 caused by satisfactory operation of fan 22, is transmitted through conduit 48 and causes a decrease in

the fluid pressure within cavity 54c of cup-shaped member 54, whereupon the atmospheric pressure within chamber 56c moves diaphragm 64 so as to effect engagement of movable contact 72 and stationary contact 88. Engagement of contacts 72 and 88 permits the electrical potential generated by heating of thermocouple 104 by the flame at pilot burner 44, to cause electric current to flow through the above-described electrical circuit including winding 37 of electromagnetic operator 36. Energization of operator 36, in turn, causes operating lever 38 to be pivoted against the force of compression spring 42 thus moving valve member 32 to its flow-permitting position relative to valve seat 34. Thus fluid fuel is permitted to flow through conduit 24, control device 26 and conduit 28 to main burner 30 where it is ignited by the flame at pilot burner 44 to provide a flame for heating of the air within the plenum chamber 16 and hence the air within heat exchanger 23. The heated air within heat exchanger 23 is then transmitted by any desired means such as a fan or blower (not shown) through duct 27 to the space to be heated, such means also bringing in cooler air through duct 25 to be heated within heat exchanger 23.

It will be noted that the aforescribed use of pressure responsive switch 50 in circuit with thermocouple 104 and winding 37 of electromagnetic operator 36 requires fan 22 to be operating satisfactorily in circulating air from within plenum chamber 16 to the chimney or stack prior to ignition of main burner 30. Such safety feature insures an adequate supply of secondary air to main burner 30 for complete combustion of the fluid fuel emitted therefrom.

Further, it will be seen that since bellows 98 and movable mounting member 94 are substantially identical with bellows 90 and movable mounting member 70, any variation in fluid pressure within plenum chamber 16 caused by changes in ambient atmospheric pressure has no effect on the differential between the control point pressure within the chamber 54c in response to which the contacts 72 and 88 engage and the ambient atmospheric pressure. This is true because both of cavities 54c and 56c are exposed to atmospheric conditions and because the opposite sides of diaphragm 64 have substantially equal effective areas. It is thus seen that any variation in atmospheric pressure within cavity 54c is also realized within cavity 56c through opening 56e in member 56, so that any increment of actuating force exerted on the diaphragm 64 and hence on the contact 72 as a result of the variation in pressure within the chamber 54c is opposed by an equal force resulting from the same variation in pressure within the chamber 56c. As a result, the pressure within the plenum chamber 16 constituting the control point pressure of the device 50 bears a fixed relation to ambient atmospheric pressure, and actuation of the contact 72 into engagement with contact 88 in response to operation of the blower 22 is assured, irrespective of variations in the ambient atmospheric pressure.

I prefer to employ bellows 90 and 98 as biasing means for initially setting diaphragm 64 in a predetermined position wherein movable contact 72 is out of engagement with stationary contact 88. Such setting can be varied by merely changing the position of adjustable end wall 96, as by varying the position of nut 102 on stud 100. As will be realized by those persons skilled in the art, the initial relative position of contacts 72 and 88 determines the biasing force of bellows 90 and 98 which must be overcome by the pressure variation within plenum chamber 16 before contacts 72 and 88 are engaged. It is thus seen that the amount of pressure variation required within chamber 16 before contact 72 will be caused to engage contact 88 is also adjusted by means of nut 102 and stud 100. It is realized that separate biasing means may be employed on one or both sides of diaphragm 64 in place of the biasing effect of either or both of bellows 90 and 98 without departing from the spirit of the present invention.

Upon removal of the pressure variation within plenum chamber 16 as caused by shut-down or faulty operation of blower 22, diaphragm 64 is returned to its initial position under the biasing effect of one or both of bellows 90 and 98, thereby separating contacts 72 and 88 and interrupting the energizing circuit for winding 37 of electromagnetic operator 36. Deenergization of winding 37 causes operating lever 38 to be rotated under the influence of spring 42 to return valve member 32 to its flow-preventing position in engagement with valve seat 34. Thus fluid fuel flow to main burner 30 is interrupted.

Fluid fuel flow to main burner 30 will be automatically interrupted, as well understood in the art, whenever thermocouple 104 is permitted to cool as by reason of extinguishment of the flame at pilot burner 44.

Although I have shown and described certain specific embodiments of my invention, I am fully aware that many modifications thereof are possible. My invention, therefore, is not to be restricted except insofar as is necessitated by the prior art and by the spirit of the appended claims.

I claim:

1. A control device comprising a pressure sensitive member having opposite sides of substantially equal area 25 and defining one wall of a pressure sensing chamber, a first electrical contact fixed within said chamber, a co-operating second electrical contact within said chamber fixed relative to said pressure sensitive member for movement therewith toward and away from said fixed contact, hermetically sealed enclosing means for said contacts comprising a first variable volume container having a fixed wall and having an opposing movable imperforate wall to which said second contact is fixed, said movable wall being fixed to and reducing the effective area of said pressure sensitive member exposed within said chamber, and means for reducing the effective exposed area of the opposite side of said pressure sensitive member an amount equal to the reduction effected by the movable wall of said container, said last-mentioned 35 means comprising a second hermetically sealed variable volume container having a fixed wall and having an opposing movable wall fixed to the opposite side of said pressure sensitive member and having an area substantially equal to the area of the movable wall of said first 45 container.

2. A control device comprising a pressure sensitive diaphragm having opposite sides of substantially equal area and defining one wall of a pressure sensing chamber, a first electrical contact fixed within said chamber, a co-operating second electrical contact within said chamber fixed relative to said pressure sensitive diaphragm for movement therewith toward and away from said fixed contact, hermetically sealed enclosing means for said contacts comprising a first variable volume container having a fixed wall and having an opposing movable imperforate wall to which said second contact is fixed, said movable wall being fixed to and reducing the effective area of said pressure sensitive diaphragm exposed within said chamber, and means for reducing the effective exposed 55 area of the opposite side of said pressure sensitive diaphragm an amount equal to the reduction effected by the movable wall of said container, said last-mentioned means comprising a second hermetically sealed variable volume container having a fixed wall and having an opposing movable wall fixed to the opposite side of said pressure sensitive diaphragm and having an area substantially equal to the area of the movable wall of said first container.
